HAIR CURLER

Frank Fuscaldo, Chicago, Ill.

Application October 2, 1939, Serial No. 297,556

9 Claims. (Cl. 132—41)

This invention relates to hair dressing devices and more particularly to hair curlers and the like.

One of the objects of the invention is the provision of a new and improved hair curler for impressing curls in the hair.

Another object of the invention is the provision of a new and improved hair curler having novel means for holding the curlers while applying the device to the hair and removing the same therefrom.

Another object of the invention is the provision of a new and improved hair curler having novel means for holding the parts in locked position on the hair while the hair is drying and being set.

A further object of the invention is the provision of a new and improved hair curler that is inexpensive to manufacture, easily assembled, efficient in use, and that is readily and easily applied to the hair.

Other and further objects and advantages of the invention will appear from the following description, taken in connection with the accompanying drawing, in which—

Fig. 1 is a plan view of the device;

Fig. 2 is a section on the line 2—2 of Fig. 1;

Fig. 3 is a cross-section on the line 3—3 of Fig. 2;

Fig. 4 is a cross-section on the line 4—4 of Fig. 2;

Fig. 5 is a perspective view of the clamping member;

Fig. 6 is a perspective view of the curling arm member;

Fig. 7 is a perspective view of the keeper; and

Fig. 8 is a section on the line 8—8 of Fig. 6.

In the use of curlers and bobby pins in dressing hair, great difficulty has been experienced in holding the curler while it is being placed in position on the hair due to the greasy-like composition used on the hair. Considerable difficulty has also been experienced in holding the parts in hair holding position. In the conventional type of curlers, the parts are so constructed that while they function properly when first used, they soon become distorted or loose and fail to hold the hair in proper position while the hair is drying. The present invention seeks to overcome these and many other objections by a simple device that is substantial in construction and provided with latching, curling and clamping means that are reliable in operation and firmly connected together.

Referring now to the drawing, the reference character 5 designates the hair curler or curler device which comprises a curler arm member 6,

a clamping member 7, pivoted to the curler arm member 6 as by means of the pivot 8, a spring 9 for forcing the clamping member toward the curler arm member, and a keeper 10 mounted on the pivot 8. The curler arm member 6 comprises a tubular portion 11, a body portion 16 and a flattened portion forming a handle or finger piece 12 having a circular opening therethrough. The flattened portion is concavo-convex in cross-section as shown at 14 in Fig. 8, the convex surface 15 being turned outwardly. The body portion 16 between the tubular portion 11 and the handle portion 12 is provided with what will be termed upstanding ears 17 and 18 having aligned apertures 19 for receiving the hinge pintle 8, Fig. 1, for holding the parts together, as will presently appear.

The outer end of the tubular arm 11 is crimped over as shown at 22 to form a rounded end on said arm. The segments 23 that are crimped over are more or less resilient and each is in the form of a frustum of a pyramid. They are curved over into contact with each other to form a smooth rounded end that will not become entangled in the hair. The segments are of such length and have their ends so shaped as to form a circular axial opening 24 in the outer end of said arm, which constitutes a resilient socket for the locking member on the keeper 10, as will presently appear.

Suitable means are provided for the circulation of air through the curler arm member 6 in order to facilitate the drying of the hair after it has been wound around the curler. As shown, a series of openings 25, preferably, though not necessarily, circular, are provided on each side of this member and the bottom of the member is, likewise, provided with similar openings 26 alternating with elongated openings 27, as shown in Fig. 2.

The clamping member 7 comprises a body portion 28 having apertured ears 29 which are adapted to be engaged by the pivot 8 extending through the ears 17 and 18 on the curler arm member 6. The body portion has a forwardly extending clamping arm 31 which is concavo-convex in cross-section with the concave surface engaging or nesting with the curler arm member 6 as shown in Fig. 3 of the drawing.

The back of the clamping arm member 31 is provided with a series of ventilating openings 50 which may be of any desired shape, those shown being alternately circular openings 32 and elongated openings 33 which are similar to the openings 26 and 27 on the back of the curler arm member 6.

The body portion 28 has a rearwardly extending flattened portion 34 which has an axial circular opening 35. The portion surrounding the opening 35 forms a handle or finger piece and is semi-circular in cross-section similar to the member 12 of the curler arm member with which it cooperates to form a handle member with the concave surfaces opposite each other. The spring 9 is wound around the pintle 8 and one end engages the finger piece or handle 12 and the other end engages the finger piece or handle 34 for forcing these handle members apart for causing the clamping member to be forced into clamping contact with the curler arm member 6.

15   Mounted on the pivot 8 is the keeper member 10. This member is U-shaped and has its ends 36 and 37 flattened and provided with aligned openings, Fig. 7, through which the pivot pin 8 is adapted to extend. The ends 36 and 37 extend 20 outwardly of the curler arm member 6 and clamping member 7 and has the loop or connecting portion 39 stamped inwardly to provide a semi-circular button or lock member 41 which is adapted to engage in the opening 24 for holding the 25 keeper in operative position on the curler arm member 6 and clamping member 7.

In the operation of the device, the keeper 10 and clamping member 7 are turned to the dotted lines positions shown in Fig. 2. In practice, the 30 keeper is turned much further than is indicated in Fig. 2, that is, it is turned to an out-of-the-way position. A lock of hair is clamped at its ends against the curler arm member by the clamping member 7 and then wound around the curler arm member 6 and clamping member 7, after which the keeper 10 is moved to the full line position in Fig. 1 and the button or semi-circular ball member 41 is snapped into the recess 24 for holding the hair in rolled up condition. After the hair 35 is dried and set, the keeper 10 is removed, the resiliency of the segments 23 permitting the ball member 41 to be released and then after the clamping member is elevated, the curling arm member is removed from the curl by an endwise 40 movement in the direction of the handle members by the operator. The openings 13 and 35 in the finger pieces or handle members permit the fleshy portion of the finger to enter this opening thereby forming a firm hold for manipulating the 45 curler member.

It is thought from the foregoing, taken in connection with the drawing, that the construction and operation of my device will be apparent to those skilled in the art and that changes in size, 50 shape, proportion and detail may be made without departing from the spirit and scope of the appended claims.

I claim as my invention:

1. In a hair curler, a tubular curler member 60 having a rounded end with an axial opening forming a resilient socket, a clamping member having a concavity engaging the outer portion of said first mentioned member, means for pivotally connecting said members together, and a wire 65 loop pivoted to said members and having an enlarged hemispherical portion in the loop and integral therewith for frictionally engaging said resilient socket.

2. In a hair curler, a tubular curler member 70 having a crimped rounded end slit radially forming a resilient recess, a concavo-convex clamping member of less length than said tubular member and pivoted thereto, a keeper member in the form of a loop pivoted to said members and coaxial 75 therewith, said keeper member having a portion

distorted to form a convex member for snapping into said recess.

3. In a hair curler, a tubular curler member having a convex outer end, the convex portion being slit radially and provided with an axial 5 opening for forming a resilient socket, a clamping member, overlapping perforated ears on said members, a keeper member of wire bent to form a loop and having flattened perforated ends, a pivot pin extending through said ends and ears 10 and headed over at each end, the connecting portion of said loop being distorted to form a button for engaging in said socket, the portions between said slits being adapted to yield to permit said button to pass thereover and seat in 15 said socket.

4. In a hair curler, a curler member comprising a body portion having upstanding perforated ears, a curved inner end handle portion having an axial opening, the rim around said 20 opening being concavo-convex in cross-section with the convex surface extending in the opposite direction from said ears, and a tubular curler section having circular ventilating openings in its side and having alternate slots and circular 25 ventilating openings in its back side and having a rounded end forming an axial opening constituting a resilient socket for receiving a button on a keeper member.

5. A keeper member for a hair curler comprising 30 a wire loop having its ends flattened and provided with aligned pivot receiving openings, the connecting portion of said loop being distorted inwardly to form a hemispherical member with the convex surface inwardly.

6. In a hair curler, a curler member formed from a flat strip of sheet metal and comprising a body portion having upstanding perforated ears, a handle portion having a curved periphery and provided with an axial opening, the rim around 40 said opening being concavo-convex with the concave opening in the direction of said ears, a tubular portion having its outer end crimped around a central opening forming a socket, a clamping member formed from a strip of flat sheet metal 45 and comprising a body portion having downwardly extending perforated ears, a handle portion having a curved peripheral edge and having an axial opening, the rim around said opening being concavo-convex with the convex surface extending upwardly, a hair clamping concavo-convex portion integral with said body portion and having ventilating openings therein, a keeper member formed from a single length of wire bent to form a loop, said loop having flattened ends having aligned perforations therethrough, a pivot pin extending through all of said perforations and headed over at each end for connecting said curler, clamping and keeper members together, and a button on said keeper member for snapping into said socket.

7. In a hair curler, a curler member formed from a flat strip of sheet metal and comprising a body portion having upstanding perforated ears, a handle portion, and a tubular portion integral 65 with the body portion and provided with elongated openings on its back and with a plurality of openings on its side for the passage of air for drying the hair when the curler member is in use, the free end of said tubular portion being slit and rounded over to form a resilient recess.

8. In a hair curler, a tubular curler member having a slit crimped curler end rounded and forming a resilient recess, a concavo-convex 75 clamping member of less length than the tubular

member, a keeper member in the form of a loop having its ends flattened, and a pivot pin extending through aligned openings in said members and headed over at each end, said loop member having a projection thereon for detachably engaging said resilient recess.

9. In a hair curler having a tubular curler member having a socket in its outer end and a clamping member pivoted together with a pivot pin, the combination of a keeper member com-

prising a metallic loop of light material having flattened ends with aligned pivot pin openings for receiving said pivot pin, the connecting portions of said loop being distorted to form a rigid holding element in the form of an enlarged hollow hemispherical portion with a convexity thereof extending inwardly toward the flattened ends for engaging in said socket for holding said keeper in operative position.
